UNITED STATES PATENT OFFICE.

JAMES SWIFT ROGERS, OF ROCKPORT, MASSACHUSETTS.

SELF-DUMPING SCOW.

SPECIFICATION forming part of Letters Patent No. 357,857, dated February 15, 1887.

Application filed September 23, 1886. Serial No. 214,332. (No model.)

To all whom it may concern:

Be it known that I, JAMES SWIFT ROGERS, a citizen of the United States, and a resident of Rockport, in the county of Essex and State of Massachusetts, have invented a new and useful 5 Improvement in Self-Dumping Scows, of which the following, taken in connection with the accompanying drawings, is a specification.

This invention relates to improvements in self-dumping scows, and it is carried out as follows, reference being had to the accompanying drawings, where—

Figure 1 represents a plan view, and Fig. 2 represents a partial side elevation and longitudinal section, of the improved scow. Fig. 3 15 represents an end view; and Fig. 4 represents a cross-section on the broken line A. B, shown in Fig. 1.

Similar letters refer to similar parts wherever they occur on the different parts of the drawings.

a is the body of the scow, having a recess, a', in its bottom, which recess extends from end to end of the scow, as shown.

25 a" is the well for receiving the stone or other material that is to be dumped from the scow. To the lower sides of the well a" are hinged a pair of hollow floatable doors, b b, as shown, and to the under sides of such floatable doors 30 are secured the respective keels b' b', that may be straight or arched, and said keels extend from end to end of the said doors, and they serve the purpose of strengthening the doors, and also for the purpose of receiving the 35 chains, links, ropes, &c., c c, by means of which the doors b b are held in a closed position against the recessed bottom of the scow while loading and transporting the dumping materials, and for this latter purpose I make on 40 the under side of each keel b' a longitudinal groove or channel, b", (shown in Figs. 2, 3, and 4,) such grooves or channels being preferably closed by means of the respective plates or covers b' b", to prevent the chains from sagging and fouling.

45 The floatable doors b b are hinged to opposite sides of the lower edges of the well a" by means of metal hinges d d, having plates d' and d", secured, respectively, to the interior sides of the well a" and to the upper side of the doors b b, the plates d' d" being each of equal length, or nearly so, to the depth of the well a", and the plates

d" d" are made as long, or nearly so, as the width of each of the doors b b, such plates serving to strengthen the sides of the well and 55 the doors, as well as to protect such parts from wear and tear when filling, unloading, or transporting the loaded scow.

As a further protection of the well sides and tops of doors, I secure to such parts, between 60 the hinge-plates d' d", respectively, to the interior of the well and tops of doors, the metal plates e e', the plates e e' being sufficiently long, or nearly so, to extend from top to bottom of the well, and the plates e' e' equal in 65 length to the width of each door b, or nearly so, as shown in the drawings.

By having a pair of hollow air-chambered doors, each of which is equal in width to one-half of the width of the lower portion of the 70 well a", or nearly so, and hinged, respectively, to opposite sides of the well a", the load can be discharged centrally from the scow without the danger of careening it, as is a common objection to that kind of self-dumping scows, 75 in which one single door of equal width with the well is used and hinged to one side of the well-room only. By having two floatable doors hinged as described, each about one-half the width of the well, and adapted to swing downward when released, the scow can be used to 80 dump or discharge its contents in very much shallower water as compared with a single-door scow.

In self-dumping scows the well a" is generally made wider at the bottom than at the top, as shown in Fig. 4, to permit a free discharge 85 of the contents of the well when the doors are released, and the latter are preferably so hung as to permit of their being swung a little back 90 of a vertical position when fully opened, and thus to form, as it were, a continuation of the inclined sides of the well. When fully open and swung back of a vertical position, the buoyant doors would be held open by reason 95 of their floatability or buoyancy, and it would require a great expenditure of power to swing the doors over what may be called their "dead-centers," and to obviate such difficulty I secure to the recessed bottom of the scow, or to 100 the movable doors, or in any other suitable manner, springs f f, as shown in Figs. 3 and 4, which springs may be made in the form of flat, elliptic, or coiled, or other well-known

- forms, as may be desired, and the object of said springs is to serve as elastic cushions or bunters against the doors when swung fully open, such springs having a tendency to swing the doors inward sufficiently to pass beyond their dead-centers, when the buoyancy of the doors will cause them to be automatically returned to the closed positions shown in the drawings.
- 10 The hollow air-chambered doors *b b* are extended longitudinally beyond the ends of well *a''*, as shown in Fig. 2, by which arrangement the buoyancy or floatability of the doors is materially increased, and the doors made to shut automatically and much faster than dumping-doors without such longitudinal extensions.
- The longitudinal sides of the scow outside of the recessed portion *a'* may be carried downward, as shown at *a'' a''* in dotted lines in Fig. 3, 20 to form side keels on a level, or nearly so, with the door-keels *b' b''*, so as to keep the scow on an even keel if left on a beach or flat at low water.
- At each end of the scow and to the deck of 25 it is secured a windlass consisting of standards or bearings *G G*, in which are journaled the chain-barrels *g g*, to which are secured the wheels *g' g'*, having perforations *g''* on their circumferences, as shown, in which a bar or 30 lever is inserted to turn the barrels *g g*, as is usual in windlasses. Between the wheels *g' g'* is secured to them, or to the common shaft on which they are fastened, the ratchet-wheel *g'*, in the teeth of which engages the pawl *h*, the 35 lower end of which is pivoted to the deck of the scow, as shown in Figs. 1 and 2. Each pawl *h* is jointed between its toothed upper end and its fulcrum, so that it may be released easily from the ratchet-wheel when it 40 is desired to dump the scow. To each end of the scow-deck is journaled a roller, *k*, on which the chains *c c* are guided from one windlass to the other, passing outside of the scow and below the doors *b b*, as shown in the drawings. 45 Instead of the single roller *k*, a pair of pulleys or shorter rollers may be used at each end of the scow, one for each of the respective chains *c c*, without departing from the essence of my invention.
- 50 To close the doors *b b* preparatory to loading the scow, it is only necessary to turn the barrels *g g* by means of hand-spikes or levers inserted in the holes in the wheels *g' g'*, or, in other words, to turn the barrels so as to cause the 55 chains to be wound tightly upon them, as shown in Figs. 1, 2, and 3, the pawls *h h* preventing the chains from being unwound until released at the proper time by the man in charge.
- The mechanism for releasing the pawls *h h* 60 from their respective ratchet-wheels *g' g'* is carried out as follows: About midway on the scow-deck, or other suitable part is pivoted, at *l*, the releasing-lever *l*, and to opposite sides of the fulcrum *l* are pivoted to said lever *l* the rods *l'' l''*, one for each windlass. The outer end of each rod *l''* is hinged to a crank, *m'*, on the rock-shaft *m*, that is located in suitable bear-

ings, *n n n*, secured to the scow-deck. *m''* is a second crank on shaft *m*, the pin on which passes through the jointed part of the pawl *h*, as shown. *l* is a locking-pin placed in a hole or socket in the scow-deck, so as to retain the lever *l* in the locked position shown in Fig. 1; but any other suitable device may be used to secure the lever *l* in a locked or unlocked position, and, if so desired, a lock and key may be added without departing from the spirit of my invention. It will thus be seen that by simply throwing over the single lever *l* the chains at both ends of the scow are simultaneously released, thus liberating the doors *b b* and allowing the scow to be instantly and even discharged.

It will be seen by reference to the drawings that the door-supporting chains are arranged 85 entirely outside of the hold or well *a''*, thus forming no obstruction whatever to the proper loading and discharge of the scow.

Having thus fully described the nature, construction, and operation of my invention, I 90 wish to secure by Letters Patent and claim—

1. A dumping-scow having the well *a''* and recessed bottom *a'* and a pair of hollow air-chambered floatable doors, *b b*, hinged, respectively, to opposite sides of the lower part of 95 the well, as and for the purpose set forth.

2. In a self-dumping scow, a pair of hollow floatable doors, *b b*, hinged to opposite sides of the lower part of the well *a''*, and having the grooved or channeled keels *b' b''*, to strengthen 100 the doors *b b*, and to receive the chains *c c*, as herein set forth and described.

3. In a dumping-scow, the springs *f f*, in combination with the scow *a* and its hinged floatable doors *b b*, said springs being adapted 105 to impart a closing movement to the doors *b b*, as set forth.

4. The scow *a*, having well *a''* and a pair of hollow floatable doors, *b b*, combined with the hinges *d d*, having the extensions *d' d''*, 110 and the strengthening and protecting bars *e e'*, arranged between the extensions *d' d''*, respectively, as and for the purpose set forth.

5. A dumping-scow having well *a''*, combined with a pair of hollow floatable doors, *b b*, hinged at the lower part of the well and extended in a longitudinal direction beyond the ends of the well and to or beyond the ends of the body of the scow, as herein set forth.

6. A self-dumping scow having the well *a''* 120 and a pair of hollow floatable doors, *b b*, hinged to opposite sides of the lower part of the well, combined with windlasses at the two ends of the scow, and chains *c c*, connecting them and carried outside of the scow without entering 125 the well *a''*, as and for the purpose set forth.

7. In a dumping-scow, the well *a''* and hollow floatable doors *b b*, hinged to the opposite sides of the lower part of the well, as described, in combination with the chains *c c*, 130 arranged outside of the scow and below the doors *b b*, the barrels *g g*, ratchet-wheels *g' g'*, pawls *h h*, and crank-shafts *m m*, arranged at opposite ends of the scow-deck, the single re-

leasing and locking lever *l*, and the rods *l' l''*, connecting the said lever *l* with the cranks *m' m''* on the shafts *m m'*, as and for the purpose set forth.

5. 8. In combination, the scow-body *a*, its well *a''*, floatable hollow hinged doors *b b'*, grooved keels *b' b''*, windlass-barrels *g g*, guide rollers or pulleys *k k*, and chains *c c*, connecting the barrels *g g* and passing outside of the scow to and below the doors *b b'*, as set forth.

9. In a scow, a pair of windlasses, and chains *c c* connecting them outside of the hinged

doors of the scow, in combination with a single releasing and locking lever, *l*, and connecting mechanism, as set forth. 15

In testimony whereof I have signed my name to this specification, in the presence of two subscribing witnesses, on this 22d day of September, A. D. 1886.
